UNITED STATES PATENT OFFICE.

GEORGE H. BRYANT, OF WINDSOR, NORTH CAROLINA.

DESIGN FOR A WASHSTAND.

45,852.

Specification for Design.

Patented June 2, 1914.

Application filed June 4, 1913. Serial No. 771,774. Term of patent 7 years.

To all whom it may concern:

Be it known that I, GEORGE H. BRYANT, a citizen of the United States, residing at Windsor, in the county of Bertie and State of North Carolina, have invented a new, original, and ornamental Design for Wash-stands, of which the following is a specification, reference being had to the accompanying drawing, forming part thereof.

The figure is a perspective view of a wash stand, showing my new design.

I claim:

The ornamental design for a wash stand, as shown.

GEORGE H. BRYANT.
